Attorney.

UNITED STATES PATENT OFFICE.

EDWARD J. MURPHY, OF WATERFORD, NEW YORK, ASSIGNOR TO W. B. ARMSTRONG CO.,
OF ALBANY, NEW YORK, A CORPORATION OF NEW YORK.

COMBINED PIPE CUTTER, GROOVER, AND REAMER.

1,237,677.

Specification of Letters Patent. Patented Aug. 21, 1917.

Application filed June 2, 1915, Serial No. 31,674. Renewed January 17, 1917. Serial No. 142,953.

To all whom it may concern:

Be it known that I, EDWARD J. MURPHY, a citizen of the United States, residing at Waterford, county of Saratoga, and State 5 of New York, have invented certain new and useful Improvements in Combined Pipe Cutters, Groovers, and Reamers, of which the following is a specification.

Reference may be had to the accompanying drawings, and the reference characters marked thereon, which form a part of this specification. Similar characters refer to similar parts in the several figures therein.

Certain objects of the invention are, by a 15 single operation, to cut off a desired length of pipe and to provide the same with a peripheral groove near the cut-end; to prevent accidentally cutting through or dangerously weakening the pipe while cutting 20 a peripheral groove therein; to maintain the accuracy of a depth-gage in connection with a pipe-groove-cutter which requires to be ground down or sharpened from time to time; and to properly finish the cut-end of 25 the pipe in the same device in which it was cut.

Other objects will appear in connection with the following description.

Figure 1 of the drawings is a view in 30 side elevation of a combined pipe-cutter-groover-and-reamer embodying my invention, applied to a section of pipe.

Fig. 2 is a front view of the same.

Fig. 3 is a view of the pipe-engaging portions of the device viewed from the side opposite that shown in Fig. 1.

Fig. 4 is a vertical section of the same taken longitudinally of the pipe on the broken line 4—4 in Fig. 1.

Fig. 5 is a similar view showing the reamer applied to the cut-end of the pipe.

Fig. 6 is a plan view of one of the cutter-supporting slide-blocks with the cutting-knife, grooving-knife and depth-gage 45 mounted thereupon.

Fig. 7 is a view in elevation of the outer side of the same.

Fig. 8 is a view in elevation of the inner side of the same.

Fig. 9 is a view partly in elevation and partly in vertical section of the same as seen from the front.

Fig. 10 is a vertical cross-section of the

groove-cutter illustrating the manner of adjusting the depth-gage in sharpening the 55 cutter.

Referring to the drawings wherein the invention is shown in preferred form, 1 is the frame of the device having a stationary jaw-member, 2, and a movable jaw-member, 3, slidably mounted on the frame by means of lugs or brackets, 4, embracing a slideway-flange, 5, on the frame.

The jaw-member, 3, can be moved toward and from the stationary jaw-member, 2, by 60 means of a hand-operated screw, 6, which passes through an interiorly threaded bearing, 7, on one end of the frame.

The other end of the frame is provided with a socket, 8, adapted to receive an operating-handle, 9, by means of which the device can be turned around the pipe to be operated upon, which pipe is closely embraced between, and supported by, the jaw-members during the cutting-and-grooving 75 operation.

Each of the jaw-members, 2 and 3, is formed with a slideway, 10, for a slide-block, 11, said slide-blocks being yieldingly actuated by springs, 12, which, under compression, tend to force the slide-blocks toward each other.

Attached to the outer side of each slide-block, 11, is a cutter, 13, for severing a pipe; and attached to the inner side of each 85 slide-block, 11, is a cutter, 14, for grooving the pipe, the cutter, 14, being somewhat shorter than the cutter, 13.

The two cutters, 13, are located in a common transverse plane, and the two cutters, 90 14, are located in a common transverse plane parallel therewith.

A depth-gage, 15, is also mounted upon each slide-block, 11, adjacent to the shorter cutter, 14.

Each slide-block, 11, thus has a cutter, 13, a cutter, 14, and a depth-gage, 15, mounted thereupon in fixed relation to the block and to each other.

The depth-gage, 15, is shorter than the 100 shorter groove-cutter, 14, a distance equal to the depth of groove desired; and the cutter, 13, is sufficiently longer than the cutter, 14, to sever the pipe before the cutter, 14, has penetrated the pipe the distance permitted by the depth-gage, 15.

The spring-induced movement of each slide-block, 11, is limited by means of a screw, 16, which engages a groove, 17, in the side of the block.

5 The movement thus permitted the blocks is sufficient to bring the depth-gages slightly beyond the pipe-engaging portions of the jaw-members, so that in applying the device to a pipe, 18, when the movable jaw, 3, is 10 forced toward the stationary jaw-member, 2, the pipe will be first engaged by the longer cutters, 13, causing the slide-blocks, 11, to be forced back into their respective slideways against the force of the springs, 12, until the pipe is closely confined between the jaw-members, after which the device is rotated upon the pipe, while the cutters, under the action of the springs, 12, are caused to penetrate the pipe, which is finally 15 severed by the cutter, 13, and grooved by the cutter, 14, to the depth permitted by the depth-gage, 15.

In Figs. 1 and 2, the pipe is shown inserted in the device with the cutters, 13, in engagement with opposite sides of the pipe to force back the slide-blocks, 11, into their respective slideways, as the movable jaw-member, 3, is forced toward the stationary jaw-member, 2.

20 In Figs. 3 and 4, the pipe is shown closely confined between the jaw-members with the slide-blocks, 11, forced back into their slideways in position to begin the cutting operation.

25 In Fig. 5, the pipe is shown still supported by the jaw-members after the pipe has been severed by the cutter, 13, and a groove, 19, formed in the pipe by the cutter, 14, the further penetration of which cutter, 14, is prevented by the engagement of the depth-gage, 15, with the outside of the pipe.

30 As the cutters, 13 and 14, require to be ground down or sharpened from time to time, I have, in order to maintain the accuracy of the depth-gage, provided a screw-and-slot connection which permits a limited movement of adjustment of the depth-gage toward and from the cutting-end of the cutter, 14, a distance equal to the depth of groove desired.

35 The depth-gage, 15, is adjustably attached to the cutter, 14, by means of a screw, 20, which passes through a slot, 21, in the depth-gage, which slot permits, when the screw, 20, is loosened, a movement of the depth-gage toward the cutting-end of the cutter a distance equal to the depth of groove desired.

40 When it is found necessary to grind down or sharpen the cutter, 14, the screw, 20, is loosened, the depth-gage is moved toward the cutting-end of the cutter, the distance permitted by the slot, 21, which brings the end of the depth-gage flush with the end of

the cutter, and the parts are firmly secured 65 in this position by setting up the screw, 20.

Both the cutter and the depth-gage are then ground down together and equally, as by an emery-wheel, until the cutter is properly re-sharpened.

70 The screw, 20, is then again loosened and the depth-gage is dropped back the limited distance permitted, leaving its end the original distance back of the cutting-end of the cutter.

75 For certain purposes of the invention, the adjustable movement of the depth-gage relatively to the cutter, 14, may be limited in any known manner.

80 As shown in the drawing, the adjustable movement of the depth-gage away from the cutting-end of the cutter, 14, is limited by either the end-wall of the slot, 21, or by the wall, 22, of a recess in the block, 11, within which the cutter and depth-gage are mounted by means of screws, 23, which screws pass through apertures in the depth-gage and cutter, 14. Said apertures in the depth-gage may be in the form of slots, 24, permitting the same degree of adjustment as 90 the slot, 21, in case it should be desired to sharpen the cutter, 14, without removing it from the block.

95 In severing a piece of pipe, the cut-end is usually left with a bur upon its edge which is objectionable, particularly if the pipe is to be used as part of an electric-conduit.

100 A further feature of my invention is a pipe-reamer whereby the cut-end of the pipe can be finished before the pipe is removed from the device wherein it was cut.

105 For this purpose I pivotally mount at 25 upon one of the jaw-members, preferably the stationary jaw-member, 2, a reamer-holder, 26, in the swinging end of which is movably mounted a reamer, 27, which is normally yieldingly withdrawn within the holder by means of a coil-spring, 28, and which can be projected out from the holder 110 by means of a handle, 29.

115 The reamer-holder is thus mounted upon the jaw-member, 2, in such a manner that its swinging end can be oscillated toward and from the neighboring cutter, 13, and the reamer, 27, is of such dimensions that it is adapted to pass through the clearance-opening, 30, in said cutter, 13, into engagement with the cut-end of the pipe.

120 During the cutting-and-grooving operation, the reamer is swung back away from the pipe and cutter, 13, in the position shown in Figs. 1 and 2, in which position it is yieldingly held by a spring-latch, 31.

125 After the cutting-and-grooving operation has been completed and before the pipe is removed from the device, the reamer is swung to a position opposite the cut-end of

the pipe and is then forced inwardly by hand through the clearance-opening, 30, into engagement with the cut-end of the pipe, while the device is rotated around the pipe 5 in the same manner as during the cutting operation.

The burs and rough edges left by the cutting tool are thus scraped off, leaving the cut-end with a smooth finished surface.

10 The aperture, 32, in the reamer-holder through which the reamer plays, is somewhat larger than the body of the reamer, permitting the reamer to adapt itself to different sizes of pipes.

15 In the reaming operation, the reamer, 27, is supported laterally by the side-walls of the clearance-opening, 30, in the neighboring cutter, 13.

I have shown a reamer having a forked 20 end adapted to embrace the edge of the pipe and finish the same both internally and externally.

What I claim as new and desire to secure by Letters Patent is—

25 1. A device of the class described having pipe-supporting jaw-members, and a cutter and a depth-gage movably mounted in fixed relation to and out of line with each other upon one of said jaw-members.

30 2. A device of the class described having pipe-supporting jaw-members, and a cutter and a depth-gage movably mounted in fixed relation to and out of line with each other upon each of said jaw-members.

35 3. A device of the class described having pipe-supporting jaw-members, a cutter and a depth-gage movably mounted in fixed relation to each other upon one of said jaw-members, and another longer cutter movably 40 mounted upon one of said jaw-members in a different transverse plane from said first-mentioned cutter.

45 4. A device of the class described having pipe-supporting jaw-members, and having movably mounted upon one of said jaw-members in fixed relation to each other in different transverse planes two cutters of different lengths, and a depth-gage for the shorter of said cutters.

50 5. A device of the class described having pipe-supporting jaw-members, a spring-actuated block slidably mounted on one of said

jaw-members, and a cutter and a depth-gage mounted out of line with each other upon said block in fixed relation thereto. 55

6. A device of the class described having pipe-supporting jaw-members, a spring-actuated block slidably mounted upon one of said jaw-members, and having in fixed relation to said block in different transverse 60 planes two cutters of different length, and a depth-gage for the shorter of said cutters.

7. A device of the class described having a cutter, a depth-gage out of line with said cutter capable of a limited movement toward 65 and from the cutting-end of the cutter, and means for detachably securing said cutter and depth-gage in fixed relation to each other in each of the extreme positions of adjustment permitted the depth-gage. 70

8. A device of the class described having a cutter, and a depth-gage with a screw-and-slot connection whereby they are detachably secured together in fixed relation to and out of line with each other with the depth-gage 75 at a distance from the cutting-end of the cutter equal to the depth of cut desired, said screw-and-slot connection permitting adjustment of the depth-gage toward the cutting-end of the cutter a distance equal to 80 said desired depth of cut.

9. In a device of the class described, and in combination, a pair of pipe-supporting jaw-members; a cutter movably mounted 85 upon one of the jaw-members and provided with a clearance-opening; and a reamer removably supported in said clearance-opening in the cutter in position to engage the cut-end of the jaw-member-supported pipe.

10. In a device of the class described, and in combination, pipe-supporting jaw-members; a cutter movably mounted upon one of the jaw-members and provided with a clearance-opening; a reamer-holder pivotally mounted upon one of the jaw-members to 90 swing to and from said cutter; and a reamer movably mounted upon the reamer-holder adapted to engage the cut-end of the jaw-member-supported pipe through said clearance-opening in the cutter. 95

In testimony whereof, I have hereunto set my hand this 10th day of May, 1915. 100

EDWARD J. MURPHY.
